UNITED STATES PATENT OFFICE.

DANIEL S. DUNN, OF BAY CITY, MICHIGAN.

ACCOUNT-REGISTER.

1,094,887.

Specification of Letters Patent.

Patented Apr. 28, 1914.

Application filed January 19, 1911. Serial No. 603,558.

To all whom it may concern:

Be it known that I, DANIEL S. DUNN, a citizen of the United States, residing at Bay City, in the county of Bay and State of Michigan, have invented certain new and useful Improvements in Account-Registers; and I do hereby declare the following to be a full, clear, and exact description of the invention, such as will enable others skilled in the art to which it appertains to make and use the same.

This invention relates to account registers and pertains more particularly to that class of account registers in which the carbon 15 copy of the purchaser's order is filed on an index sheet of metal or other suitable material, there being a series of such sheets indexed alphabetically or in any other convenient manner for ready reference.

20 The object of my invention is to provide an account register of the class above referred to, with means whereby all of the accounts may be readily inspected, filed or removed by a number of persons simultaneously, thereby greatly facilitating the clerical work of operating an account system.

A further object is to provide an account register capable of containing a large number of accounts in a small space, yet allowing each account to be readily inspected, and furthermore to arrange the account sheets (on which the orders are mounted in groups or books) so that a group of the sheets may be removed from the register without disturbing the remaining sheets in the register. All of the sheets comprising one group are fastened together and removable from the register as a single book. The purpose of this construction is to enable a number of 30 clerks to work upon the accounts in the various books simultaneously, and to permit all of the books to be stacked and filed in the vault or other safe place when the register is not in use.

45 A further object is to provide a novel means for filing the orders on the metal sheets.

With these and certain other objects in view, which will appear later in the specification, the invention consists in the devices 50 illustrated in the accompanying drawings, in which—

Figure 1 is a side elevation showing the working parts of an account register of my 55 improved construction; Fig. 2 is a top plan

view of the upper revolving disk with one book in place; Fig. 3 is a perspective of one of the brackets by which the sheets are bound into groups and the groups removably mounted on the disks; Fig. 4 is a perspective of a book of sheets, a second book being indicated by dotted lines to show how a number of books may be piled together for storage; Fig. 5 is an enlarged sectional detail taken on the line $x-x$ of Fig. 1; and Fig. 6 is a perspective detail showing the springs by which the bills are held to the sheet, the sheet being broken away in part.

In the drawings, 1 indicates a base or other suitable support, which may be in the form of a pedestal as shown. Fixed to the base 1 is a central upright standard 2. Revolvably mounted on the standard 2 are disks 3 and 4 connected by a hollow spindle 5, the disks and spindle being adapted to revolve together in either direction around the standard. I prefer to make the upper disk 4 in the shape of a polygon, although it may be of circular or other shape. The disk 4 is provided with a plurality of pairs 6 of holes in alignment with corresponding holes 7 in the lower disk. The pairs of holes 6 and 7 receive the pins, by means of which the books of sheets may be readily mounted upon or removed from the disks.

In Fig. 4 is illustrated one of such books. It consists of a number of sheets 8 preferably made of sheet metal, having rearwardly and downwardly projecting lugs 9, 9^a at their ends. The downwardly projecting lugs are received in apertured brackets 10, 10^a so that each sheet is hinged to and may be turned in the brackets like the leaf of a book, the two brackets 10 and 10^a serving as binders for the sheet. The lower end 9^b of each lug 9 is upset to prevent the lugs from coming out of the brackets. Each bracket is provided with a pair of downwardly projecting pins 11 and 11^a adapted to be received in the holes 6 and 7 respectively so that the book of sheets can be attached to the disks by simply inserting the pins into the holes, and can be removed by merely lifting the book.

The entire register may be revolved around the upright standard so that two or more persons may work at different sides of the case at the same time, either filing orders or figuring accounts. When desired the books may be lifted from the case, stacked

as indicated in Fig. 4, forming a compact package, and stored in the vault for safe keeping.

I have also devised an improved means 5 for attaching the orders 12 to the sheets 8. This means is illustrated in detail in Figs. 5 and 6, in which 13 is a flat strip of metal riveted or otherwise secured at its lower part to the plate 8 in horizontal position, 10 the upper part 13^a of the strip being folded outwardly to form a pocket in which the bottom edge of the bill 12 rests. The upper edge of the strip is slotted as at 14, to form a lip 14^a which is bent downwardly 15 to engage a rod 15. Around the rod 15 is wound a spring wire 16, one end 16^a of which presses against one face of the sheet 8 and the other end 16^b presses against the opposite face, the extremities of the wires 20 being bent to form flattened loops 17, 17^a to better hold the bill against the sheet 8. The lower end of part 16^b passes through a perforation 13^b in the strip 13 and sheet 8, as indicated in Figs. 5 and 6. Both spring 25 clips are thus formed of a single piece of wire.

I prefer to make each sheet 8 of sufficient size to hold four orders on each face, thereby giving capacity for eight accounts on 30 each sheet, and I prefer to mount the sheets in groups of five or six to each book, although any other number of sheets may be employed. By this means any book of say forty-eight accounts may be readily taken 35 from the register, used at some other place, and quickly restored thereto as easily as a single sheet could be removed from an ordinary register. It is also possible for a number 40 of accounts while in the register, to be inspected by a number of persons at the same time, thereby expediting the figuring

up of a large number of accounts or the arranging of a great number of orders.

A number of devices may be combined with my improved register if desired, as for 45 instance a revolving case 18 for use as a display rack, as a receptacle for spices or other articles, or for any other desired purpose, the case being mounted on the upwardly projecting end of the spindle. 50

While I have shown and described my improved register as adapted to the filing of orders and bills such as are commonly used in retail stores, it is obvious that it may also be adapted for filing other sheets used 55 in different kinds of business, by simply making the sheets and springs of proper size to take the papers to be filed.

Having described my invention, what I claim and desire to secure by Letters Pat- 60 ent, is:—

In an account register, the combination with a standard, of an upper and a lower polygonal disk having holes therein in proximity to each edge, said disks revolvably mounted on said standard, pairs of brackets adapted to be removably attached to said disks, each bracket comprising a plate provided with projecting pins adapted to be received in the holes of said disks and 65 formed with a plurality of openings near its outer edge, a plurality of inflexible sheets adapted to carry papers, said sheets pivotally secured to said openings of each 70 pair of brackets. 75

In testimony whereof, I affix my signature in presence of two witnesses.

DANIEL S. DUNN.
